UNITED STATES PATENT OFFICE.

HERBERT G. IRWIN, OF SPUR, TEXAS.

DEVICE FOR CLEANING ELECTRODES OF MAKE-AND-BREAK SPARK-PLUGS.

1,275,035

Specification of Letters Patent. Patented Aug. 6, 1918.

Application filed December 3, 1917. Serial No. 205,195.

To all whom it may concern:

Be it known that I, HERBERT G. IRWIN, a citizen of the United States, residing at Spur, in the county of Dickens and State of 5 Texas, have invented certain new and useful Improvements in Devices for Cleaning Electrodes of Make-and-Break Spark-Plugs; and I do hereby declare the following to be a full, clear, and exact description of the invention, such as will enable others skilled 10 in the art to which it appertains to make and use the same, reference being had to the accompanying drawings, and to the letters and figures of reference marked thereon, which 15 form a part of this specification.

This invention relates to new and useful improvements in devices for cleaning electrodes of make and break spark plugs, and the object in view is to produce a simple 20 and efficient device of this nature so arranged that the electrode may be cleared from carbon or other foreign substances without removing the plug from the cylinder of the engine.

25 My invention consists of further details of construction, combinations and arrangements of parts which will be hereinafter fully described, shown in the accompanying drawings and then specifically defined in the 30 appended claim.

I illustrate my invention in the accompanying drawings which, with the letters of reference marked thereon, form a part of this specification and in which:

35 Figure 1 is a central vertical sectional view through a spark plug.

Fig. 2 is a bottom plan view, and

Fig. 3 is a top plan view.

Reference now being had to the details 40 of the drawings by numerals:

1 designates a spark plug adapted to be attached to the cylinder of an engine, and mounted in an apertured portion thereof is a stationary electrode tube containing the 45 axially movable electrode 3, having a beveled shoulder 3^x, adapted to frictionally engage the lower end of the tube in which it is mounted, and being held in contact therewith through the medium of the coiled 50 spring 7 which bears between the terminal

10^x upon the cable 10 and a nut 6 fitted over a circumferentially threaded portion of said tube. The tube has an insulation 5 about the same separating the tube from direct contact with the plug, and 11 designates a contact 55 ring fastened to the lower end of the electrode 3. A thumb screw 8 is mounted upon the upper threaded end of the electrode 3 and is keyed thereto by means of the pin 9 which forms means for imparting a rock- 60 ing or oscillating movement to the electrode 3. Mounted in a vertical opening in the plug 1 is an oscillating electrode 2, having a handle 2^x keyed thereto, and the lower end of the electrode 2 projects below the bottom 65 of the plug and has a laterally extending terminal 12 adapted to be thrown in contact with the circumference of the ring 11 when it is desired to clean the contact surfaces, this being accomplished by giving a 70 rotary movement to the electrode 3 when the contact portion 12 is held against the ring 11.

By the provision of a device embodying the features of my invention it will be noted 75 that means is afforded whereby any deposit of foreign matter, such as carbon, upon the contact ring 11 may be cleansed by oscillating the electrode 2 so that the contact point 12 will engage the ring 11 and after which by 80 rotating the ring through the medium of the thumb nut the contact surfaces may be cleaned.

What I claim to be new is:

A device for cleaning electrodes of make 85 and break spark plugs, comprising a flanged shell having parallel openings formed therein, a tube fitted in one of said openings and having a flange at its lower end, and a nut fitted about its upper end, the inner marginal 90 edge of the flange being beveled, an electrode mounted within said tube and having a cylindrical head at its lower end, with a beveled shoulder engaging said beveled edge of the flange, a collar about said head below 95 the beveled shoulder, a winged nut mounted upon the upper threaded end of the electrode, a connection intermediate said nut and shoulder adjacent thereto, a conical-shaped spiral spring interposed between the 100

latter and said nut, a movable electrode passing through the other opening in the shell, and having a laterally extending finger, with a contact lug thereon, and a handle fixed to the upper projecting end of said movable electrode.

In testimony whereof I hereunto affix my signature in presence of two witnesses.

HERBERT G. IRWIN.
